(57) **CLAIM**

The ornamental design for an illuminatable signage device, as shown and described.

DESCRIPTION

FIG. 1 is a perspective view of an illuminatable signage device for placement on a roof of a vehicle or a suitably dimensioned mobile environment, under a first embodiment. FIG. 2 is a front view of the illuminatable signage device of FIG. 1.

FIG. 3 is a back view of the illuminatable signage device of FIG. 1.

FIG. 4 is a right side view of the illuminatable signage device of FIG. 1.

FIG. 5 is a left side view of the illuminatable signage device of FIG. 1.

FIG. 6 is a top view of the illuminatable signage device of FIG. 1; and,

FIG. 7 is a bottom view of the illuminatable signage device of FIG. 1, excluding the unclaimed portions of the illuminatable signage device of FIG. 1.

The broken lines shown in the drawings are for the purpose of illustrating the environment of the illuminatable signage device, and form no part of the claimed design.
